UNITED STATES PATENT OFFICE.

WILLIAM JOHN MITCHELL, OF MELROSE HIGHLANDS, MASSACHUSETTS, ASSIGNOR OF ONE-HALF TO NEHIMIAH W. SMITH, OF MELROSE HIGHLANDS, MASSACHUSETTS.

SASH-FASTENER.

No. 892,537.

Specification of Letters Patent.

Patented July 7, 1908.

Application filed January 21, 1908. Serial No. 411,952.

To all whom it may concern:

Be it known that I, WILLIAM JOHN MITCHELL, a citizen of the United States, residing at Melrose Highlands, in the county of 5 Middlesex and State of Massachusetts, have invented a new and useful Sash-Fastener, of which the following is a specification.

This invention relates to sash locks, and has for its object to provide means whereby 10 an upper or a lower window sash, or both, may be opened a short distance and be securely locked in such position against all outside efforts to further open the window. This result is accomplished by a simple, 15 cheap, and easily operated device to be fastened on the upper side of the top rail of the lower sash at either side and engage the upper sash, the adjacent side of the window frame, or both.

20 With this and other objects in view, the invention comprises the novel construction, combination and arrangement of parts hereinafter described, claimed and illustrated in the accompanying drawing forming a part of 25 this specification in which—

Figure 1 is a perspective view of the improved sash lock applied to a window, a part only of the window being shown. Fig. 2 is a horizontal sectional view of the sash lock enlarged and detached from the window. Fig. 3 is a sectional view on the line 3—3 of Fig. 2. Fig. 4 is a bottom plan view of the casing, without the locking bolts, and Fig. 5 is a perspective view of one of the locking bolts. 35 Similar reference characters are used for the same parts on all the figures.

A indicates the lower sash, B the upper sash and C the window frame. Fastened to the upper side of the top rail of the lower 40 sash A and at one side thereof close to the window frame C is the sash fastener D consisting in this instance of a casing 1, secured to the lower sash by screws 2, through which casing two locking bolts 3 and 4 are adapted 45 to slide and engage respectively an opening in the upper sash B and one in the window frame C.

The casing 1 is substantially square in plan view and reaches across the sash rail from its 50 inner to its outer side. Three sides of the casing are straight, but the side adjacent the window frame is of irregular formation, it having a curved indentation 5 to receive the sash cord and an angular inset 6 at the outer 55 rear corner to extend around the parting

bead. Diagonally across the casing from the inset 6 the corner 7 of the casing is cut away at an angle for a purpose to be described later.

Formed in the under side of the casing 1 are two curved grooves 8 and 9 in which the 60 respective locking bolts 3 and 4 slide when moved into and out of engagement with the upper sash and the window frame. The grooves 8 and 9 open, respectively, on the sides of the casing next the upper sash and 65 the window frame, and curving towards each other they unite before reaching the angular corner 7 into a single groove 10, equal in width to the two grooves.

The locking bolts 3 and 4 are alike in construction and form, but they are oppositely curved as represented in Fig. 2. Each locking bolt has a locking end 11 preferably of cylindrical form which is projected outwardly to engage an opening in the window frame 70 or upper sash when it is desired to lock the sash in either open or closed position. The remaining portions 12 of the locking bolts are rectangular in cross section with flat operating fingers 13 curved on their upper edges 75 and projecting from the inner end of each bolt. Near the locking ends 11 of the bolts are shoulders 14 designed to abut against a shoulder 15 in the wide groove 10 of the casing, see Fig. 3, and prevent the withdrawal of the bolts from the casing.

The window frame C has two openings 16, preferably bushed with metal to prevent undue wear. The openings in the upper window sash are formed in a metal plate 17 90 screwed to the face of the sash and flush therewith. The lower hole in the upper sash and in the window frame, which are not shown, are used for locking the window when closed. The other opening 16 in the window frame will receive the locking bolt 4 when the lower sash is raised. When the upper sash only is to be opened, the locking bolt 3 will be engaged with the central perforation 18 in the plate 17, but if both upper and 100 lower sash are to remain open the bolt 3 will enter the upper perforation 19 in the plate 17. To prevent the bolts 3 and 4 from wearing the wood sash, a thin metal plate 20, preferably of the same size and outline as the 105 casing, is fastened to the sash by the screws 2 which hold the casing in place.

A sash lock constructed as above described, will permit the windows of a house to be opened for ventilation and securely 110

locked against further opening from the outside while the tenants of the house absent themselves. The sashes are not to be opened wide enough to admit rain so that no attention need be paid to the windows during rainy weather.

The fingers 13 are flattened on their sides and curved on their upper edges to prevent the windows being forced through the medium of a bent wire engaging the upper edge of either locking bolt back of the finger. When made as described the curved upper edge of the finger gives no hold for a bent wire or other object which may be used in an attempt to open the window.

I claim:—

1. A sash lock comprising a casing having two curved grooves therein and a curved lock bolt slidable in each groove, provided with an operating finger arranged for independent or synchronous operation.

2. A sash lock comprising a casing having two curved grooves therein and curved independently operative locking bolts slidable in said grooves, each bolt having an operative finger in close proximity to the other and adapted to be projected at their locking end at a right angle to each other, said operating fingers being adapted to be simultaneously grasped by the finger and thumb of one hand.

3. A sash lock comprising a casing having two curved grooves therein joined together at one end into a single groove, curved independently operative locking bolts slidable in

35 said groove their locking ends at a right angle to each other and adapted to engage the one in openings on the upper sash and the other in openings in the window frame when said casing is attached to the top of the lower sash.

4. A sash lock comprising a casing having two curved grooves in their under side joining each other at one corner of said casing, a curved independent locking bolt slidable in each groove, one end of each bolt emerging 45 from the casing at said corner adjacent each other and having a flattened operating finger with a curved edge, and a wear plate on the bottom of said casing below said locking bolt.

5. A sash lock comprising a casing having two curved grooves in its under side joining each other at one corner of said casing to form a wide groove with a shoulder extending across the same, a curved independent locking bolt slidable in each groove and emerging 55 from said wide groove side by side and having each an operating finger and a shoulder adapted to engage the shoulder in the groove and limit the movement of the bolts in one direction.

In testimony that I claim the foregoing as my own, I have hereunto affixed my signature in the presence of two witnesses.

WILLIAM JOHN MITCHELL.
